UNITED STATES PATENT OFFICE.

CHARLES B. CLARK AND JAMES T. LAMBERT, OF DETROIT, MICHIGAN;
SAID LAMBERT ASSIGNOR TO SAID CLARK.

STOVE-PIPE DAMPER.

SPECIFICATION forming part of Letters Patent No. 235,514, dated December 14, 1880.

Application filed November 3, 1880. (No model.)

To all whom it may concern:

Be it known that we, CHARLES B. CLARK and JAMES T. LAMBERT, both citizens of the United States, residing at Detroit, in the county of Wayne and State of Michigan, have invented new and useful Improvements in Stove-Pipe Dampers, of which the following is a specification.

Our present invention relates to stove-pipe dampers provided with detachable handles; and it consists, first, in the combination, with the damper-disk having a radial socket formed by straps arranged to bridge over a slot in the disk, of the damper-spindle made in two parts, with their outer ends connected by a spring-handle; second, in the combination, with the damper-disk having a radial socket formed by straps arranged to bridge over a slot in the damper and a lug extending into the socket near the inner terminus thereof, of the damper-spindle composed of two expandable halves connected at their outer ends by a spring-handle, and formed with a notch at one or both of the inner ends of said spindle for engaging with the said lug for the purpose of retaining the spindle in the damper-disk and cause it to move in a lateral direction sufficient to hold the damper in the pipe at any desired point of adjustment, all as more fully hereinafter set forth.

In the drawings, Figure 1 is a top or plan view of the damper with its spindle connected therewith, the damper being illustrated as applied to a stove-pipe which is shown in section. Fig. 2 is a perspective view of the damper-disk. Fig. 3 shows, in perspective, the spindle detached from the damper, and Fig. 4 is a section taken transversely through the spindle on the line xx , Fig. 3.

In the drawings, the letter A refers to the damper, which consists of a circular metallic disk, preferably of cast metal, and formed with, or having secured to, its periphery in any suitable manner one of the journals, B, which, when the damper is arranged within the stove-pipe, passes through an opening in the stove-pipe, as herein illustrated.

The damper is formed with a central opening, C, to admit of a moderate draft, while

the damper-faces are in horizontal planes within 50 the stove-pipe; or, if desired, such opening may be dispensed with and the damper made somewhat smaller than the area of the stove-pipe, either of these features being common in this class of dampers.

The journal D of the damper, which, as diametrically opposite to the above-mentioned journal B, is formed by a slightly-contracted portion of the detachable damper-spindle E.

The radial socket e of the damper, which 60 receives the detachable spindle, is formed by bridging over with three straps a slot extending from a point near the central opening, C, out to the periphery of the disk, these straps being cast with the damper and arranged so 65 that the strap F at the inner, and the strap F' at the outer, terminus of the radial slot both project out from one face of the damper, while the remaining strap, G, projects out from the other face of the damper at a point about intermediate of the two straps F F'. The detachable damper-spindle, which fits in the socket thus formed, is composed of a split stem or spindle, E', the two halves of which are connected at their outer ends by a ring-shaped 75 handle, E², having sufficient elasticity to cause the halves of the stem to spring apart, as illustrated in Fig. 3. In the outer side of each one of the inner ends of the halves of the spindle is formed a notch, I, and a lug, K, for 80 engaging either one of these notches after the stem has been inserted into the socket, is formed at one of the points of juncture between the inner strap, F, and the disk, so as to extend into that portion of the socket which 85 is bridged over on one side of the disk of the said strap.

It will be seen that the split spindle is flattened along two sides and rounded upon its other sides, the notches I being made to extend into one of the flattened portions of each half of the spindle at points upon a line taken diametrically through the spindle, so that, no matter which flattened side of the split spindle is uppermost, one of the notches will always be in proper position for the engagement of the lug therewith. The split in the spindle continues from the inner end thereof through

the journal portion thereof to the handle, and between the spindle and its handle each half of the spindle is provided with a segmental flange, which flanges, when the two halves of the spindle are forced together, constitute a collar adapted to bear against the outer side of the stove-pipe, while the spindle is fitted to the damper.

In introducing the split spindle into the socket the halves of the spindle will be forced together until one of the notches arrives at a point opposite to the lug, and then the halves will expand so that the lug will be received into such notch, and thereby lock the damper and the spindle together, and at the same time bind the pipe at the journal-bearing sufficiently to hold the damper in any desired position.

To admit of the detachment of the spindle from the damper, the sides of the notches are inclined, so that by drawing upon the spindle its halves will be brought together, so as to effect the disengagement of the notch from the lug.

Having thus described our invention, what we claim is—

1. The combination, with the damper-disk having a radial socket formed by straps arranged to bridge over a slot in the disk, of the damper-spindle made in two parts, with their outer ends connected by a spring-handle, substantially as described.

2. The combination, with the damper-disk having a radial socket formed by straps arranged to bridge over a slot in the damper and a lug extending into the socket near the inner terminus thereof, of the damper-spindle composed of two expansible halves, connected at their outer ends by a spring-handle, and formed with a notch at one or both of the inner ends of said spindle for engaging with the said lug, substantially as described.

In testimony whereof we have hereunto set our hands in the presence of two subscribing witnesses.

CHARLES B. CLARK.
JAMES T. LAMBERT.
